ALEXANDER TRAILL, OF VANCOUVER, BRITISH COLUMBIA, CANADA.

FLOOR-POLISHING MOP.

1,304,413.

Specification of Letters Patent. Patented May 20, 1919.

Application filed June 20, 1918. Serial No. 241,026.

To all whom it may concern:

Be it known that I, ALEXANDER TRAILL, a citizen of the Dominion of Canada, residing at Vancouver, in the Province of British Columbia, Canada, have invented certain new and useful Improvements in Floor-Polishing Mops, of which the following is a specification.

This invention relates to a floor dusting or polishing mop of that class wherein a strip of woolen or cotton fringed fabric is removably secured to the mop head that it may be readily taken off for washing or renewal.

15 The improvements are directed to the particular construction of the supporting frame of the mop head, enabling the fringed fabric to be more readily applied or removed without the requirement of securing attachments such as bolts, wires or tapes.

Further, and this forms the most important improvement, the fringed fabric does not only extend around the outer edge of its supporting frame but is carried within the 25 area of the outer edge of it, thus affording an increased dusting and polishing area of mop head, and the central portion being nearer the connection to the handle is more rigidly supported and will therefore stand 30 a higher polishing pressure.

The particular means by which these several objects are attained are fully set forth in the following specification, reference being made to the drawings by which it is accompanied, in which:

Figure 1 is a vertical section through the mop head supporting frame showing the handle withdrawn from its connection to the head, being a section on the line 1—1 in Fig. 2.

Fig. 2 is a sectional plan on the line 2—2 in Fig. 1.

Fig. 3 is a cross section of the central connection of the head on the line 3—3 in Fig.

45 1, and

Fig. 4 is a plan of the handle attachment.

The supporting frame is formed of stout wire doubled parallel at a width approximately that of the tubular body of the mop head fabric 2. The mid-length of this wire is formed as a loop 3 where it is secured to the handle attachment to be described later.

From the loop 3 each end is doubled outward and backward at 4 and at the heel or back of the head is turned at 5 outward and

forward and the forwardly turned ends 6 are angled inward toward the middle line where they closely approach one another. At 6 the wire is doubled upward on itself and returns parallel in a vertical plane to 60 the outline 6, 5, 4, 3, and at a distance therefrom to fit the tubular portion of the fringed fabric 2.

At the center the two extreme ends are secured at 7 by any suitable means in the upwardly turned end of a plate 8 which fits within the upwardly turned edges of a plate 9 within which the central loop 3 is fitted. The plate 8 is secured to the plate 9 by two rivets 10, thus permanently securing the 70 frame 3, 4, 5, 6 to the central plates 9 10.

To the middle of the plate 9 is secured a screw 11 which passes through and projects above the plate 8 by which screw the fabric supporting frame is secured to the end of 75 the mop handle. The plates 8 and 9 and the loop 3 and ends 7 are secured together at such angle to the plane of the head frame as is convenient for the operator.

Along the free ends 6 of the wires doubled 80 in a vertical plane may be passed the opposite ends of the tubular body of the fringed fabric 2, which forms the mop. When passed from the ends 6 along each 85 side of the frame and around the bends 5, they will form a heart-shaped mop which is a convenient form for enabling corners to be reached, either for polishing or dusting, but beyond this bend 5 the mop fabric 2 may be further passed along the parallel central portions to the bends 4 at which the loop 3 and ends 7 of the frame are connected to its handle attachment, so that in distinction to the common practice in mop holding frames, the fringed material is not only carried around the edge of the mop head but is projected within the area so inclosed, thus providing an additional hold for retaining the mopping material on the frame without any supplementary fastening, such as tapes 90 or the like. It further provides a fuller and more compact head having a larger amount of polishing material.

The handle 15 may be connected to the head frame of the mop in any convenient 105 manner. As here shown the end of the handle has a saw cut within its ferrule 14 into which cut a straight piece of flat iron 12 is inserted. The inner end of 12 has prongs 13, see Fig. 4, which are driven into 110

the end wood of the handle and a pin 16 is driven through an aperture in the ferrule, handle and the iron 12.

It will be noticed that the resilience of the outer edge of the frame is very much reduced where the frame is connected at the center to the mop handle, so that the hardest polishing pressure is there applied and the outer edge gives the lighter finishing pressure.

10 The strip of mop fabric is removed from the head frame by a manual pull applied where the strip bridges between the free ends 6 of the frame. This pull withdraws 15 the strip from both sides of the frame simultaneously.

Although the frame is described as made of doubled wire and is heart-shaped, and thus affords a simply made and thoroughly 20 efficient supporting frame, I do not desire to be confined to the use of such wire nor to the outline form of the frame given, or the manner of its attachment to the handle; as the essential feature of the invention resides 25 in the use of a frame onto which a continuous length of mop fabric may be passed to not only inclose a certain outline of head, but to provide the area within that outline with the mop fabric, and this in a 30 manner that the fabric will retain its connection to the head frame without any supplementary fastening.

Having now particularly described my invention, I hereby declare that what I claim 35 as new and desire to be protected in by Letters Patent, is:

1. A floor polishing mop head, comprising in combination, a central attaching portion provided with means for attachment 40 of the same to a handle, a frame of wire doubled vertically from each end toward the center and the doubled ends doubled horizontally from the center toward one an-

other and in the same plane each doubled end bent outward and backward beyond the 45 end of the central loop and then outward and forward to bring the two free looped ends into proximity, the central loop and the adjacent ends of the wire being secured to the central attaching portion, and means 50 for removably securing a handle to the central portion.

2. A floor polishing mop head, comprising a stout wire, the ends of which are doubled inward in the same plane to adjacent 55 the midlength and the doubled ends are doubled at the middle in a plane at right angles to the first mentioned bend, and thereafter the doubled ends are bent outward and backward parallel to the middle 60 bend from positions adjacent the ends of the inwardly bent wire, each doubled end being again turned outward and forward to a position beyond the backward bend at the center where the free loop ends are brought 65 into proximity, means for securing the center of this wire frame to a handle, said means comprising the upturning of the central loop and the two ends of the wire adjacent to the angle which the handle is desired 70 to have with the mop head frame, a central plate with its opposite edges turned upward to fit the central loop, a second plate adapted to fit within the upturned edges of the first named plate, said second 75 plate having an upturned end apertured to receive the ends of the wire adjacent the middle loop in which apertures the ends of the wire are secured, means for riveting the two plates together whereby the frame is 80 strongly secured at the center, and means for attaching the handle of the mop to the connected plates.

In testimony whereof I affix my signature.

ALEXANDER TRAILL.
